UNITED STATES PATENT OFFICE.

IRVIN M. COOK, OF CLEVELAND, OHIO.

ELECTRIC TERMINAL BOX.

1,302,137.

Specification of Letters Patent. Patented Apr. 29, 1919.

Application filed December 27, 1917. Serial No. 209,154.

To all whom it may concern:

Be it known that I, IRVIN M. COOK, a citizen of the United States, residing at Cleveland, in the county of Cuyahoga and

5 State of Ohio, have invented certain new and useful Improvements in Electric Terminal Boxes, of which the following is a specification.

This invention relates to terminal boxes 10 for telephone or other cables, such boxes being frequently mounted on telephone poles or the like for the purpose of housing and supporting the cable terminals and connections.

15 The object of the invention is to provide a housing which can be permanently attached to a pole or other support and which can be readily opened for the purpose of making connections when desired, without removing the box from the support. A further object of the invention is to provide a weather proof housing which is readily accessible to the lineman and in which all parts of the connections can be readily got 20 at for the purpose of work thereon.

The device comprises a fixed back or part, a hinged plate or board which carries the terminals or connectors, and the sliding cover which can be removed for access to 25 the interior. The terminal board is so arranged that either the front or the rear connections are easily accessible.

The details of the invention will be apparent from the following description and 30 accompanying drawings in which:-

Figure 1 is a perspective view of the box with the cover partly raised;

Fig. 2 is a vertical section on the line 2—2 of Fig. 3;

40 Fig. 3 is a section partly broken away on the line 3—3 of Fig. 4;

Fig. 4 is a horizontal section on the line 4—4 of Fig. 3.

Referring specifically to the drawings, 45 indicates the back part of the box or housing. This comprises a recessed casing, with sides 7 flared outwardly, and a top flange 8. This casing has rearwardly projecting ears 9 by which it may be attached to a telephone pole or other support by bolts or other suitable devices. At the bottom, this 50 box section has a removable bottom piece 10 with holes 11 through which the cables (not shown) may be entered from below. The

bottom piece slides in guides 10^a. Since the 55 cables and the manner of connecting the same form no part of the invention, they are not shown.

The partition or panel board which carries the fuse strips and the binding posts, 60 comprises a frame 12 with panels 13 and 14 of insulating material secured thereto, and the frame has vertical forwardly projecting flanges 15 which bridge the panels 14 and are provided with openings 16 for the fuses 65 (not shown). The frame and panels comprise a unitary structure which fits against the front of the back section of the box. The frame 12 has a horizontal flange 17 at the bottom provided with cable openings 18, 70 and the whole frame is hinged to the back section by means of projecting ears 19 which are pivoted to ears 20 on the bottom of the back section 6 by means of hinge pins 21.

The sliding cover or front section of the 75 box comprises a front plate 22, sides 23 and the top 24 which when in position laps the top 8 of the back section, as shown in Fig. 2. The sides 23 have inwardly projecting flanges 25 which engage slidably behind the 80 margins 26 at the front edges of the sides 7 of the back section, this cover or front part being open at the bottom. It has a hand cleat 27 by which it may be lifted.

Access to the front of the panel board 85 may be obtained by removing the front section of the cover. This is done by lifting or sliding it up until the flanges 25 clear the edges 26. The front of the panel board is thereby exposed for work on the front sections, without disturbing any other part of the device. To get at the rear of the panel board, the screw 30 at the top is removed, and the whole frame 12 and the panels carried thereby are free to swing forwardly 90 and outwardly on the hinge pins 21, thereby exposing the back of the board and permitting the rear connections to be made. The box is closed by swinging up the panel board and inserting the screw 30, and then 100 sliding the cover or front section in place from above. It will be noted that the whole panel board may be assembled as a unitary structure before it is placed in the box, and when the box sections are united, a complete 105 housing is formed which protects the panel board and its connections from the weather.

For the purpose of holding in position the

cables which are entered through the holes 11 of the box section, I provide a cross rod or spindle 31 which is supported on suitable lugs fastened to the sides of the box section. 5 In a similar manner I provide a lower cross rod or spindle 31^a which serves to take care of the slackened wire strands and preventing same from spreading over the box. 32 is a simple locking device to hold the cross rod 10 31^a securely in position.

I claim:

1. An electric terminal box comprising a back casing section having hinge members projecting downwardly below the bottom 15 thereof, a panel board frame having an outwardly projecting flange at the bottom thereof and also having downwardly projecting hinge members pivoted to said hinge members below the bottom of the box, whereby said frame may swing to reversed position away from and below the casing, and a front casing section removably attached to

said rear section and adapted to inclose said frame and its flange.

2. An electric terminal box comprising a 25 back casing section having a removable bottom piece slideable into and out of position at the bottom of the casing, a panel board frame hinged to said back section below said bottom piece and adapted to swing 30 to or from said back section, to open or closed position and to confine said bottom piece when in closed position, said frame having a bottom flange projecting forwardly, and a removable front casing section 35 in sliding engagement with the rear section and adapted to lap the front edge of said flange.

In testimony whereof, I do affix my signature in presence of two witnesses.

IRVIN M. COOK.

Witnesses:

JOHN A. BOMMHARDT,
G. N. ROSENBERG.
